CLAIM

U.S. PATENT DOCUMENTS

The ornamental design for a mobile device display screen with graphical user interface as shown and described.

DESCRIPTION

D820,850 S * 6/2018 Tekamp D14/485
D850,472 S * 6/2019 Maguire H04L 67/535
D14/485
D865,795 S * 11/2019 Koo D14/488
D918,246 S * 5/2021 Getman D14/488
D936,696 S * 11/2021 Soccorsy D14/488
D946,594 S * 3/2022 duPont D14/485
D951,290 S * 5/2022 Hart D14/488
D952,676 S * 5/2022 Soccorsy D14/489
D956,084 S * 6/2022 Roy D14/492
D964,407 S * 9/2022 Segerud D14/486
D964,408 S * 9/2022 Segerud D14/486

The FIGURE is a front view of a mobile device display screen with graphical user interface embodying a fleet page of the new design.

The broken line showing of a display screen in all views forms no part of the claimed design.
